UNITED STATES PATENT OFFICE

EDWARD M. SWARTZ, OF BOSTON, MASSACHUSETTS, ASSIGNOR TO KEYSTONE MFG. CO., OF BOSTON, MASSACHUSETTS, A CORPORATION OF MASSACHUSETTS

DESIGN FOR A TOY VEHICLE

Application filed February 1, 1932. Serial No. 42,686. Term of patent 14 years.

To all whom it may concern:

Be it known that I, EDWARD M. SWARTZ, a citizen of the United States, residing at Boston, in the county of Suffolk and Commonwealth of Massachusetts, have invented a new, original, and ornamental Design for a Toy Vehicle, of which the following is a specification, reference being had to the accompanying drawing, forming a part thereof.

The figure of the drawing is a view, in perspective, of a toy vehicle showing my new design.

The dominant feature of my design is the provision at the top-side of a toy vehicle of a seat and a steering handle both of enlarged proportions relatively to the miniature body permitting the toy to be ridden and guided by the child user.

I claim:

The ornamental design for a toy vehicle substantially as shown and described.

EDWARD M. SWARTZ.
